KNOCKDOWN CORNER CABINET

Harold C. Bullard, Cambridge, Mass.

Application June 24, 1942, Serial No. 448,222

3 Claims. (Cl. 312—142)

This invention relates to knock-down wooden china closets of the type designed to fit into the corner of a room.

It aims to devise an article of this character which can be erected quickly by following very simple directions and with the aid of only the simplest tools, can be easily dismantled and moved to another location and which, when dismantled, can be disposed in a compact form suitable for shipment.

The nature of the invention will be readily understood from the following description when read in connection with the accompanying drawings, and the novel features will be particularly pointed out in the appended claims.

In the drawings,

Figure 1 is a front elevation of a cabinet constructed in accordance with this invention;

Figure 2 is a vertical, sectional view approximately on the line 2—2, Fig. 1;

Fig. 3 is an angular rear view of the front or face section of the cabinet shown in Fig. 1 with some parts broken away;

Fig. 4 is a horizontal, sectional view of the front section of the cabinet, the plane of section being taken just above the counter rail;

Fig. 5 is a vertical, sectional view on the line 5—5, Fig. 1;

Fig. 6 shows part at the right-hand bottom corner of the portion of the cabinet shown in Fig. 3;

Fig. 7 is a front elevation of a part of the rear upright;

Fig. 8 is an angular view of one of the shelves; and

Fig. 9 is a plan view of the cabinet showing it positioned in the corner of a room.

Referring first to Figs. 1 to 4, inclusive, the construction there shown comprises two lateral front uprights 2 and 3 which may, for convenience, be referred to as "pilasters." These members are connected by cross pieces consisting of a threshold 4, a counter rail 5, and a pediment 6. The pilasters may each be made from a single board or plank of suitable thickness, or they may be built up as may best suit the manufacturing requirements of individual designs, and the rear surfaces of each of these members are slotted, as indicated at 7, to receive the front corners of a series of shelves 8. Preferably each shelf is made of plywood, as best shown in Fig. 8, has approximately the shape of an isosceles triangle with a stiffening rib 10 of plywood secured to it by staples, or other suitable fastenings, and is provided with an angular re-

inforcing or finish strip 11 at its forward edge which also may be stapled to it. Usually the forward edge of this reinforcing piece 11 will be grooved or otherwise ornamented, this piece ordinarily consisting of a short section of molding. Also, as shown in Fig. 8, the edge 11 of the shelf 8 is inset with reference to the ends a—a or, in other words, the latter parts project forwardly by a sufficient distance to bottom in the slots

10 7—7 in the pilasters 2 and 3. This is true as to all of the shelves except the topmost one 8', the ends of which rest on the upper ends of the pilasters, as best shown in Fig. 2. The rearward ends or corners of all the shelves, except that at

15 the top of the cabinet, fit into slots formed in a rear or corner upright 12, Fig. 5, and these corners are secured to said upright by screws driven diagonally through portions of the shelves and into the upright. The front edges or corners 20 of the shelves are similarly secured to the pilasters by screws driven in like manner through the shelves and into the parts 2 and 3. At all of these points an interlocking engagement is provided which holds the parts accurately in their proper 25 relationship to each other and against movement in three directions so that all that the screw associated with each joint has to do is to pull the parts of that joint into their interlocking relationship to each other, and hold them there.

30 This construction thus makes a very stiff, sturdy assembly, even without any side covering for the rearwardly extending edges of the shelves, although such covering can be used, if desired. Preferably the rear upright 12 is notched or 35 slotted at its forward side to receive both the straight rear edge of each shelf and also to receive the reinforcing rib 10. Such a notch construction is shown at b in Fig. 7. At this corner the shelf is interlocked with the upright against 40 movement relatively thereto in all directions except a forward direction.

The counter rail 5, the threshold 4, and the cross rail a of the pediment are screwed to the pilasters and either these parts or the pilasters themselves, or both, are notched to provide a strong 45 secure joint. They divide the opening at the face of the closet into upper and lower sections, the former being here shown as fitted with a hinged sash 13 and the latter with a door 14.

50 In making this cabinet all of the manufacturing operations are performed at the mill on the pilasters, threshold, counterrail, pediment, rear upright and the shelves, and such assembling as may be required of parts of these units is there performed, so that when these units are ready

for shipment they may, at times thereafter, be readily assembled or erected into a complete structure.

The parts of the front section are so designed that erection is facilitated by first securing the counterrail 5 to the two pilasters 2 and 3, as best illustrated in Figs. 3 and 4. It will be observed that this rail has an ornamental nose piece c secured to it and cooperating with it to provide slots at its opposite ends, into which the adjacent edges of the pilasters fit. The latter are drilled to receive two screws 15—15, Figs. 3 and 4. Also, the rearward part of the counterrail fits into notches provided in the pilasters by cutting away the edge reinforcing strip 16. Thus these parts have an interlocking connection with each other and the counterrail and threshold space the pilasters properly, when the parts are secured together, for the location of the pediment and the driving of the screws which hold it in place.

Next the threshold 4 preferably is placed in position with its ends in the notches formed to receive it at the lower ends of the pilasters. Also, as shown in Fig. 6, the threshold is provided with a notch or cut-out 17 to receive the lower left-hand corner portion of the base block 18 when the end of the threshold is properly butted against the back surface of said base block. The same construction is provided at the opposite end of the threshold so that both corners of the threshold are interlocked with the pilasters and are secured thereto by vertical screws 21, the heads of which are received in a groove 22, Figs. 5 and 6, formed in the bottom of the threshold.

When these parts have been connected together, they secure the pilasters in parallel relationship so that the pediment may then be easily set accurately in place and secured by the screws 23. Preferably, also, the rear surface of the pediment is grooved near its opposite ends, as shown at 24, and drilled to receive the screws 25 which hold the top shelf 8' in its operative position. The forward projecting edges of this shelf extend into slots formed by spacing the upper ends of the pilasters 2 and 3 from the lower end of the pediment 6, as clearly shown in Fig. 2.

Next the shelves are inserted in the slots of the pilasters, are secured there by the screws, as above described, and the rear corners of the shelves are then similarly set into the slots in the rear upright 12 and screwed to them. The doors 13 and 14 may then be hung.

This completes the assembly of the essential parts of the cabinet, but it is usually preferable to secure strips of edge beading 26—26, Figs. 1 and 4, to the grooved edges of the pilasters where they will fill the crack that otherwise would be left between these outside edges and the wall when the cabinet is set into place. This operation, however, is customarily performed on the job or site. Note that an ornamental groove cut in edge beading 26—26 makes it easy to drive nails at same angle as wall line.

It may here be noted that the molding strips on certain of the shelves act as stops for the sash 13, one of these shelves being so positioned that the molding 11 engages the lower inside margin of the frame of the sash along the area d, Fig. 5, just above the counterrail 5. Also, that this rail preferably is rabbeted, as shown in Fig. 5, to act as a stop for the upper margin of the door 14.

If it should be desired to dismantle the cabinet, either for removal or shipment, that can

readily be done because of the fact that all of the parts which must be separated are secured together by screws. It will also be noted that all of these screws are of the same size so that any confusion which otherwise might be caused by different sizes of screws is avoided.

In an article of this character, particularly when the shelves are supported only by their corners, there is much likelihood of these parts becoming warped or sprung. Any substantial trouble from this source, however, is avoided in the construction shown by making the shelves of plywood and reinforcing them by the pieces 10 and 11, Figs. 8 and 9, located at right angles to each other.

A typical method of securing the cabinet in its operative position in the corner of a room is illustrated in Fig. 9 where the meeting walls of the room are shown in cross-section at 27. Two long wood screws, one of which is shown in Fig. 9 at 28, may be inserted through holes 30—30, Fig. 5, in the rear upright 12 and driven into the studding, some part of which usually is located at the corner of a room.

The invention thus provides a knock-down type of corner cabinet which can readily be assembled into a sturdy and substantial structure with no other tools than a screw-driver and possibly a hammer to tap the shelves into their slots if they fit rather tightly. The construction lends itself to various types of ornamentation suited to go with furniture of different designs, and to finishing operations which may either be performed in the mill or by the ultimate purchaser, as circumstances may require.

While I have herein shown and described a preferred embodiment of my invention, it will be evident that minor variations may be made in it without departing from the spirit or scope of the invention.

Having thus described my invention, what I desire to claim as new is:

1. A knock-down corner cabinet consisting essentially of a front section including two pilasters 45 at opposite sides thereof, a plurality of triangular shelves and a rear corner upright; the rearward surfaces of said pilasters having slots formed therein extending horizontally from approximately the outer edges of the pilasters to points spaced from their inner edges, each of said shelves 50 having tongues extending forward from the opposite end portions of its front edge, each shelf having a recess extending along its front portion between said tongues and the tongues fitting 55 into said slots, the forward surface of said rear corner upright being slotted horizontally to receive the rear corners of said shelves, said slots in the pilasters and the portions of the shelves fitting into them forming joints constructed to hold the shelves against lateral movement relatively to said front section, and fastenings securing said tongues and the rear corners of the shelves in the slots in said pilasters and in said upright, respectively, so that said shelves, said tongues, said front section and said upright form, 60 without the aid of other parts, a rigid self-sustaining structure.

2. A knock-down corner cabinet according to preceding claim 1, in which said front section is itself of knock-down construction and comprises said pilasters, a threshold, a counterrail, and a pediment, said threshold and said counterrail having end portions shaped to cooperate with complementary parts of said pilasters to form interlocking joints with the latter and to space the

pilasters apart by a predetermined distance suited to the requirements of the pediment, said joint sections being drilled to receive screws for drawing the parts of the joints securely into interlocking relationship, and the upper ends of said pilasters and said pediment being drilled to receive additional screws for securing these parts together.

3. A knock-down corner cabinet according to preceding claim 1, in which said front section is itself of knock-down construction and comprises said pilasters, and transverse members connecting them, including a pediment, a threshold and a counterrail secured, respectively, to the tops, bottoms and middle portions of the pilasters, and

5 dividing the space between said pilasters into upper and lower sections, a sash to fit in one of said sections and a door to fit in the other, two of said transverse members having ends shaped to cooperate with complementary parts of said pilasters to form interlocking joints with the latter and to space the pilasters apart by a predetermined distance suited to the requirements of the third of said transverse members and also to accommodate said sash and said door, said joint sections being drilled to receive screws serving to draw the members of the joints securely together into interlocking relationship with each other.
